UNITED STATES PATENT OFFICE.

ARTHUR DARBY WACK, OF FERGUSON, MISSOURI.

MAIL RECEIVING AND DELIVERING APPARATUS.

No. 925,966.

Specification of Letters Patent.

Patented June 22, 1909.

Application filed December 24, 1908. Serial No. 469,056.

To all whom it may concern:

Be it known that I, ARTHUR DARBY WACK, a citizen of the United States, residing at Ferguson, in the county of St. Louis and 5 State of Missouri, have invented a new and useful Mail Receiving and Delivering Apparatus, of which the following is a specification.

This invention relates to apparatus for 10 delivering and receiving mail at railroad stations, the object of the invention being to provide simple mechanism whereby the interchange of mail can be effected while the train from which mail is to be received and 15 to which mail is to be delivered is passing the station at high speed.

Another object is to provide mechanism of 20 this character which can be set up for use along a single track or a double track railroad without requiring different constructions for the two kinds of railroads.

Another object is to provide mechanism by means of which the interchange of mail 25 can be effected without danger of injuring the mail pouch or other object being delivered, no part of the mechanism coming into contact with said object at any time during the operation of said mechanism.

With these and other objects in view the 30 invention consists of certain novel details of construction and combinations of parts hereinafter more fully described and pointed out in the claims.

In the accompanying drawings the preferred form of the invention has been shown.

In said drawings:—Figure 1 is a perspective view of the complete apparatus and showing the positions of the parts immediately prior to the interchange of mail. Fig. 40 2 is an enlarged plan view of one of the frame-holding arms, the head of said arm being shown by dotted lines in open position.

Referring to the figures by characters of reference 1 designates a standard designed 45 to be located adjacent the car tracks, and this standard is provided at its upper end with oppositely extending arms 2 and 3, said arms as well as the standard being formed of any preferred material such, for example, 50 as angle-iron, although it is to be understood that it may be formed of any other material desired. Secured to the end portion of each of the arms is a socket member 4 in the form of a metal strap riveted or otherwise fastened at its ends to the arms, there being a 55 notch or slot 5 in the upper edge of the strap

as indicated at 5 to receive the end portions of the receiving and delivering members. The receiving member consists of an arm 6 having a head 7 at one end and so proportioned as to fit snugly within the socket member 4, while the arm 6 is designed to rest within the notch 5. A stem 8 extends downwardly from the other end of the arm 6 and constitutes a bearing for the sleeve 9 formed at one end of an engaging arm 10. An angular hook 11 is formed at the free end of the arm 10 and constitutes means for retaining the delivered article or object upon the arm 10, as hereinafter set forth. Any 70 suitable means may be provided for preventing sleeve 9 from becoming displaced on the stem 8. For example, a bearing or retaining pin 12 may be extended through the lower portion of the stem 8. A locking device, 75 preferably in the form of a sliding bolt 13, is mounted on the arm 6 and is designed to engage the sleeve 9 so as to hold the arm 10 extended at right angles to the arm 6 and in either direction therefrom, according to the 80 direction in which the car is moving relative thereto.

The delivering member on the standard 1 preferably consists of a head 14 detachably seated in one of the socket members or straps 85 4 and having an extension 15 thereon designed to rest in the notch within said member. An arm 16 is pivotally mounted on said extension and is designed to be locked in alignment therewith by means of a bolt 90 17 or other suitable fastening means, said bolt being preferably held in place by means of a spring 18. The arm 16 is provided at its outer end with a head 19 from which extends a finger 20 disposed at right angles 95 thereto, the outer end of said finger being beveled and one end of the head 19 being correspondingly beveled as indicated at 21. A retaining block 22 is hingedly connected to the beveled end 21 of the head 19 and 100 has a transverse slot 23 in its free end designed to receive a tongue 24 formed at one end of a receiving block 25. This last mentioned block is hingedly connected with the beveled end of the finger 20 and when the 105 two blocks 22 and 25 are in their normal positions with the tongue 24 resting within the slot 23, a rectangular opening 26 is formed between said blocks 22 and 25 and the head 19 and finger 20. Springs 27 are 110 secured to the head and bear upon the respective blocks 22 and 25, so as to hold them

normally closed. Said springs however are designed to yield sufficiently to permit the retaining blocks to swing outwardly into open position, as indicated by dotted lines 5 in Fig. 2. The opening 26 is designed to receive one side of a holding frame 28, preferably rectangular in outline, and provided with a stud 29 outstanding from said side of the frame and designed to bear upon 10 the head 19. When the frame is thus held it projects beyond the end of arm 16 and in a vertical plane. A ring 30 may be arranged upon the lower portion of the frame to receive a chain 31 or other fastening device 15 used for securing a mail pouch "A" or the like to the frame.

The mechanism carried by the car "B" is an exact duplicate of that supported by the standard 1. Holding straps or socket 20 members 32 are secured to the wall of the car at opposite sides of the door-opening "b", and these straps have notches 33. The notch of one of the straps receives an extension 34, projecting from a head 35 designed 25 to be detachably seated within the retaining socket, and an arm 36 is pivotally mounted as at 37 upon extension 34, and has a locking bolt 38 for holding it in alinement with the extension. A head 39 is formed at the 30 outer end of arm 36 and in all respects this head and the parts connected thereto are constructed in the same manner as the head hereinbefore described. The other retaining member 32 is detachably engaged by a 35 head 40 formed at one end of an arm 41 from which a stem 42 extends, said stem constituting a bearing for a sleeve 43 located at one end of an engaging arm 44 on which a hook 45 is produced. Arms 41 and 44 40 are secured at desired angles to each other by means of a sliding bolt 46, although it is to be understood that any other suitable locking means may be utilized if preferred. The head 39 is designed to engage a frame 45 47 similar to the frame 28 and having a ring 49 thereon for the reception of a chain 50 or other suitable fastening device, designed to engage a mail pouch "C" or the like. A stud 51 extends from the frame 47 50 and bears on head 39, so as to hold the same against vertical displacement while engaged by the head.

As the arm 44 is pivotally mounted on the stem 42, it can be swung toward the car 55 door "b": This is also true of the arm 36. While the arms are thus located a frame 47, to which a pouch "C" is attached, can be placed within the head 39, the frame being held in such position by the retaining blocks 60 which are hingedly connected to the head. The arm 36 may then be swung outwardly into alinement with the extension 34 and locked by means of the bolt 38. The engaging arm 44 can then be swung outwardly 65 and secured by the bolt 46, said arm 44 be-

ing arranged parallel with the side of the car and extending away from the supported frame 47. The apparatus upon the car is thus set and ready for the interchange of mail. It is to be understood that the arm 70 41 is to be arranged at the advancing side of the car door, while the arm 36 is to be located at the opposite side of said door.

The apparatus at the stations where the interchange of mail is to be effected is prepared for use by swinging arm 16 into alinement with the extension 15 and locking it. The pouch "A" to be delivered is then secured to frame 28 and said frame fastened to the head 19, and by placing it thereagainst and permitting the retaining blocks 22 and 25 to fold thereinto. Arm 10 is then extended at right angles to the arm 6 and in the direction of the approaching car.

As the car passes the standard 1 the hooked end 45 of arm 44 will enter the frame 28 and at the same time the frame 27 will move into engagement with the hooked end 11 of the arm 10. The two arms 6 and 16 are preferably spaced apart a distance 50 equal to the distance between the arms 36 and 41, so that the two frames 28 and 47 will be simultaneously engaged by the arms 44 and 10. The frames will be pulled away from the heads 19 and 39 by the arms 44 and 10, the springs 27 yielding sufficiently under these conditions to permit the blocks 22 and 25 to swing into their open positions as indicated by dotted lines in Fig. 2. As soon as the frames are withdrawn from the heads 100 they drop upon the arms 44 and 10, and the hooks on said arms serve to prevent the frames from becoming displaced. After the interchange has been effected the arms can be swung inwardly, and the frames, with 105 the pouches suspended therefrom, removed into the car and on to the platform respectively.

It will be seen that this apparatus is very simple in construction, and, by providing 110 the frames and engaging arms, the interchange of mail is positively effected without danger of injuring the pouches. Although the apparatus is particularly designed for effecting the interchange of mail-bags, it 115 may also be used for delivering other objects, such as packages of merchandise, etc.

It is also obvious that various changes may be made in the construction and arrangement of the parts without departing 120 from the spirit or sacrificing the advantages of the invention. For example, an arm 41' may be extended upwardly from arm 41 and in vertical alinement with the stem 42, and another arm 6' may be extended upwardly 125 from the arm 6 and in vertical alinement with the stem 8. These arms 41' and 6' constitute means for positively preventing the frames from swinging back on to the arms 41 and 6 respectively.

What is claimed is:—

1. In apparatus of the class described a supporting structure, a reversible arm detachably connected thereto, alining stems projecting in opposite directions from the arm, a hooked member pivotally mounted upon one of the stems, and means upon the arm for engaging said member to hold it fixed with relation to the arm.
2. In apparatus of the class described a supporting structure, an arm extending therefrom, a holding frame, a head upon the arm, receiving blocks pivotally mounted upon the head and means for holding the blocks yieldingly in contact with the frame to support said frame against the head.
3. In apparatus of the class described a supporting structure, retaining members carried thereby, arms detachably supported by said members, a holding frame, means upon one of the arms for yieldingly and detachably engaging a portion of the frame to support it, and a hooked member pivotally connected to the other arm.
4. In apparatus of the class described a supporting structure, a retaining member thereon, a head detachably engaging said re-
- taining member, an arm pivotally connected to the head and mounted to swing in the direction of the supporting structure, a head 30 upon the arm, pivotally mounted receiving blocks upon the head, a holding frame detachably engaged by the head and blocks and supported thereby, and means for holding the blocks yieldingly in contact with the 35 frame.
5. The combination with a stationary structure, a holding frame detachably supported thereby, and an engaging arm carried by said structure; of a movably supported mechanism including a detachably supported holding frame and an engaging arm, said arms being positioned to simultaneously engage the respective frames and detach them from their supporting structures.

In testimony that I claim the foregoing as my own, I have hereto affixed my signature in the presence of two witnesses.

ARTHUR DARBY WACK.
